UNITED STATES PATENT OFFICE.

PATRICK J. O'BRIEN, OF BAY BULLS, NEWFOUNDLAND.

WINDOW-SASH LOCK.

Application filed May 24, 1924. Serial No. 715,580.

To all whom it may concern:

Be it known that I, PATRICK J. O'BRIEN, a citizen of Newfoundland, and a resident of Bay Bulls, Newfoundland, have invented 5 a new and Improved Window-Sash Lock, of which the following is a full, clear, and exact description.

This invention has relation to locking devices and has particular reference to a locking device for window sashes.

The present invention contemplates for its principal object a sash lock which further constitutes a means for moving the sash.

The invention furthermore comprehends a sash lock which functions to retain the sash in open position as well as in a closed position, whereby the window may be effectually locked in a partially open position and against movement to a further open position from the exterior.

As a still further object the invention resides in the provision of a sash lock and lifting device which is extremely simple in its construction and mode of operation, inexpensive to manufacture and produce, highly efficient in its purpose, and capable of being readily applied to or removed from the sash.

With the above recited and other objects in view, the invention resides in the novel construction set forth in the following specification, particularly pointed out in the appended claim and illustrated in the accompanying drawings, it being understood that the right is reserved to embodiments other than those actually illustrated herein to the full extent indicated by the general meaning of the terms in which the claim is expressed.

In the drawings—

Figure 1 is a view illustrating the sash locking devices constructed in accordance with the invention in applied position.

Fig. 2 is a fragmentary enlarged view thereof with parts shown in section.

Fig. 3 is a transverse sectional view taken approximately on the line indicated at 3—3 in Fig. 2.

Fig. 4 is a horizontal sectional view taken approximately on the line 4—4 of Fig. 2.

Fig. 5 is a face view of the stationary section of the sash locking member.

Referring to the drawings by characters of reference, A designates generally a window sash which includes side rails B mounted in the window frame C for vertical

sliding movements and retained in place by the retaining strips or window stop elements D.

The sash locking device constituting the invention consists of a latch member having a stationary section 10 and a movable section 11, the former being stationarily mounted on the inner face of the side rail B and the latter being mounted upon the stationary member for lateral or transverse swinging movement. As illustrated the means for mounting the sections consist of a screw 12 which passes through aligned openings in the sections 10 and 11 and is anchored in the side rail B of the sash and a pin 13 which passes through the stationary section 10 and is anchored in the side rail B. The outer section 11 is slotted as at 14 to receive the pin 13 which further serves as a stop element for limiting the latter swinging movement of the section 11. Adjacent its lower end the latch section 11 is provided with laterally projecting locking lugs 15 and with a forwardly projecting manipulating handle 16. The inner side face of the retaining strip or window stop member D is provided with a plurality of spaced keeper openings 17 preferably lined by a metallic plate 18 having openings 19 aligning with the keeper openings 17.

In use and operation of the device the manipulating handle 16 serves both as a means for swinging the latch section 11 to engage and disengage the locking lugs 15 in the keeper openings and as a means for raising or lowering the sash. Preferably two of the devices are employed in connection with each sash as illustrated in Fig. 1. When it is desired to raise and lock the sash, the handles 16 are grasped and the latch sections 11 are swung laterally inward as illustrated in dotted lines in Fig. 2, thereby disengaging the locking lugs 15 from the keeper openings, after which the window sash may be raised or lowered to the desired point, the sections 11 being swung laterally outward to engage the locking lugs 15 with the keeper openings.

It is to be understood that the device may be applied in an inverted position relative to the position shown in the drawing without departing from the spirit of the invention.

I claim:

A window sash locking device comprising a latch member including a stationary

section and a laterally movable section mounted on the side rail of a window sash, a locking lug on the movable section, a keeper plate carried by the window frame and having a plurality of vertically spaced keeper openings for receiving the locking lug, a handle member constituting respectively a means for effecting engagement and disengagement of the lug with the keeper

10 openings and for moving the sash, a common means extending through one end of

each of the latch sections for pivotally associating the movable section with the sash, a slotted portion in the opposite end of the movable section, and a common means extending through said slotted portion and through the stationary section for holding the latter section against movement and for constituting a stop to limit the lateral swinging movement of the movable section.
